Primary Examiner — Angela J Lee

(57) **CLAIM**

The ornamental design for display screen with graphical user interface, as shown and described.

DESCRIPTION

FIG. 1 is a front view of a display screen with graphical user interface showing my new design; and, FIG. 2 is a front view of a second embodiment thereof. The broken line showing of the display screen or portion thereof on all views is not part of the claimed design.

1 Claim, 2 Drawing Sheets(56)
